UNITED STATES PATENT OFFICE.

LA VERNE W. NOYES, OF CHICAGO, ILLINOIS.

BOOK-HOLDER.

SPECIFICATION forming part of Letters Patent No. 349,660, dated September 21, 1886.

Application filed May 6, 1886. Serial No. 201,394. (Modol.)

To all whom it may concern:

Be it known that I, LA VERNE W. NOYES, a citizen of the United States, residing at Chicago, in the county of Cook and State of Illinois, have invented certain new and useful 5 Improvements in Book-Holders, which are fully described in the following specification, reference being had to the accompanying drawings, forming part thereof, wherein—

10 Figure 1 is a rear elevation. Fig. 2 is a perspective of one of the sliding supports. Fig. 3 is a vertical section through the slide-bearing of the sliding supports and the slide-arms therein.

15 This invention is designed to be an improvement upon a book-holder for which there was granted to me a patent, No. 335,085, dated January 26, 1885.

It consists in providing a spring to uphold 20 the book-shelves, tending to close them together and clamp the book, and in making the horizontal slides, on the outer ends of which the shelves are pivoted, triangular in cross-section, or having their contiguous faces oblique to the line of pressure applied by 25 the clamping-screw, so that when clamped by said screw they shall tend to bind on all sides against the bearing, in which they are thus clamped, and thus be prevented from gaining 30 play in the plane of their contiguous faces, whereby, sometimes, I have found the clamp-screw gradually loosened and the effectiveness of the clamp destroyed.

A is the central support, composed of the 35 two members A' and A², pivoted together. The member A' terminates below in a spindle, A¹⁰, whereby it is adapted to be connected to an upright standard. The screw A³ serves to lock the two members A' and A² together at 40 any desired inclination. This structure is not herein claimed, because it is claimed in my patent above mentioned. The member A² of the central support has the back-support A²⁰, and underneath it the transverse rectangular 45 aperture constituting a slide-bearing, A²¹, and screwed through the front wall of said slide-bearing the clamp-screw B.

C C are brackets, which support the folding shelves D D. They are themselves supported by having their horizontal arms C passed through the slide-bearing A²¹, being in-

serted one from each side, and lying in contact and clamped by the clamp-screw B. In order that said clamping may render them tight in said slide-bearing vertically as well 55 as horizontally—that is, may cause them to bind against the top and bottom walls of the bearing, as well as against the rear wall and against the clamp-screw in front—I bevel their contiguous faces, C¹⁰, as seen in Fig. 3, 60 preferably cutting from corner to corner, and leaving them each right-angled triangular in cross-section, as shown. They are thus caused to slide, the one up against the top wall and the other down against the bottom wall of the bearing, so far as there is play 65 in that direction, while they are clamped together by the clamp-screw forcing them back against the rear wall. The brackets C have horizontal spindles constituting the shelf-pivots C² and the stop-tooth C³, and in the same 70 vertical transverse plane with the latter the catch or rigid tooth C⁴. The shelves D are secured to the shelf-plates D' D', which have the pivot-bearings D¹⁰ for the shelf-pivots C², and 75 the pivot-bearings also for the latches E E. Said latches terminate at one end in the thumb-pieces E' and at the other end in the hooks or catches E². Said hooks E² are adapted to engage the stop-teeth C³ and the catches C⁴, as 80 seen in Fig. 1, wherein one shelf is raised, showing the latch engaged with the tooth C³, and the other shelf is horizontal, showing the latch engaged with the catch C⁴.

Around the spindles C² are coiled the springs 85 F, stopped at one end against the lug c on the bracket and at the other end against the stop d' on the shelf-plates. The springs are coiled, so that they tend to throw the shelves up, folding them together in vertical position, so as to 90 clamp between them the book, which rests its back upon the back-support A²⁰. The length of the latch and the position of the hook E² is such that it engages the stop-tooth C³ at the position when the shelf is vertical, and engages 95 the catch C⁴ at the position when the shelf is horizontal, and the upper surface of the stop-tooth is in such position that the shelf-plate collides with it just at the position when the hook E² engages the catch C⁴, so that when the book-shelves lie horizontal they are positively 100 locked in both directions, and when they stand

vertical the engagement of the hook E^2 about the tooth C^3 also locks them in both directions. A spring, G , is provided, acting against the latches, tending to cause them to engage with 5 the stop-tooth C^3 and with the catch C^4 .

I claim—

1. In combination with the shelf-plates and the brackets having the shelf-pivots C^3 and the catches C^4 , the springs stopped against the 10 plates and against the brackets, and tending to fold the shelves up toward each other, and the latches E , pivoted on the shelves and engaging the catches on the brackets, substantially as set forth.
- 15 2. In combination with the shelf-plates and the brackets having the shelf-pivots, the catches C^4 and the stops C^3 , the springs tending to fold the shelves up toward each other, and the latches on the shelves engaging the catches when 20 the plates meet the stops, substantially as set forth.
- 25 3. In combination with the central support and the horizontally-sliding brackets sustained thereby, having the shelf-pivots and the catches C^4 , the springs stopped against the shelf-plates and against the brackets and tending to fold the shelves up together, and the latches on the shelves engaging the catches, substantially as set forth.
- 30 4. In combination with the brackets having the shelf-pivots, the stop-tooth C^3 , and the catch C^4 , the shelf-plates pivoted thereon and provided with the springs to throw them up, and the latches pivoted on the shelves and having 35 the notch to engage the tooth C^3 when the shelves are folded and the catch C^4 when they are open, substantially as set forth.
- 35 5. In combination with the brackets having

the spindles C^2 to serve as pivot-bearings for the shelves, the shelves pivoted thereon, and 40 the springs coiled around the spindles and stopped at one end against the bracket and at the other end against the shelves, and tending to fold the shelves together, and the means for fastening the shelves open, substantially as set 45 forth.

6. In combination with the central support having the transverse slide-bearing for the shelf-sustaining brackets and provided with the clamp-screw, the shelf-sustaining brackets having their slide-arms in contact within said slide-bearing, the contiguous faces of said arms being oblique to the direction of pressure exerted by the clamp-screw, substantially as set forth.

7. In combination with the central support 55 having the parallel-sided transverse slide-bearing, and provided with the clamp-screw B , the shelf-sustaining brackets having their slide-arms in contact within said slide-bearing, said slide-arms having oblique faces in contact, substantially as set forth.

8. In combination with the pivoted shelves rocking upward and toward each other from their horizontal position, springs reacting against stops rigid with the shelf-pivots and 60 tending in all positions of the shelves to fold them together, and locking devices to hold them horizontal against the reaction of said springs, substantially as set forth.

Signed at Chicago, Illinois, April 26, A. D. 70
1886.

LA VERNE W. NOYES.
